MALLET

Elmer E. Hosier, Delaware Water Gap, Pa.

Application May 18, 1936, Serial No. 80,435

8 Claims. (Cl. 273—83)

This invention relates to improvements in mallets; and, more particularly, a mallet designed for games such as croquet and the like.

The usual mallet head is made of wood with the stick imbedded in a recess formed in the mallet head. Such a construction is open to many objections. The wood of the mallet head splits, warps when exposed to weather, and readily transmits shock to the handle and is easily separated from the handle causing much inconvenience to the player.

The prime object of my invention is to produce a mallet head of rubber composition which may be formed by molding.

Another object is to provide a composition rubber mallet head, utilizing a minimum of material with a maximum of supporting strength.

Still another object is to provide a composition rubber mallet head with the maximum striking surface, minimum material and maximum reinforcing strength.

Another object is to provide a mallet head which will not warp, chip or split and remain firmly engaged to the handle.

Other objects will be disclosed in the specification and claims forming a part of this application.

In the drawing:

Figure 1 is a side elevation of the mallet head with the handle broken away;

Figure 2 is a vertical section taken on the line 2—2 of Figure 1;

Figure 3 is a section taken on line 3—3 of Figure 1;

Figure 4 is a section taken on line 4—4 of Figure 1; and

Figure 5 is a section taken on the line 5—5 of Figure 3.

Referring to the drawing, in which similar parts are designated by like numerals:

Numerical 6 designates a mallet head of the croquet type having striking faces 7 and 8. In practice a mallet head of rubber composition has been used, but it is obvious that other compositions having resilient qualities and capable of being molded may be used within the scope of my invention.

Intermediate the striking faces 7 and 8 is formed a recess 9 having threads 10 formed therein to receive a handle 11 of wood. The bottom 12 of the mallet head 6 presents a smooth continuous surface between the two striking faces 7 and 8 connecting and forming a part of the edges 13 and 14 of the striking faces 7 and 8. The bottom 12 is diamond shaped and rounded

to conform with the general contour of the cylindrical mallet head 6. The broadest portion of the diamond shaped bottom is at 15, and directly beneath the recess 9. The other two ends of the diamond contact the striking faces 7 and 8 at 15' and 16 to form supporting points for said striking faces 7 and 8. The top face 17 of the mallet head 6 corresponds in shape and contour to the bottom 12 contacting the striking faces 7 and 8 at 18 and 19 to form supporting points for said striking faces. The side faces 20 and 21 are diamond shaped having concave faces, the edges 22, 23, 24, and 25 tapering in to contact the bottom 12 and top face 17 at 26, 27, 28, and 29 forming a supporting trusswork of maximum strength and minimum material. Adjacent to each striking face 7 and 8 are four triangular indentations 30 having their maximum depth adjacent the striking faces 7 and 8 and tapering toward the surface so as to reach the surface at 26, 27, 28, and 29. The handle 11 is shown without threads so as to make frictional contact with the threads 10 formed in the recess 9.

It is obvious from my description that I have produced a mallet far superior to the usual wooden cylindrical head. In my mallet head by having the body cut-away in back of the striking surfaces, greater resiliency is produced and the reactionary force from the striking surface is more readily dissipated. By having the bottom and top smooth and in the same plane as the edges of the striking faces, the striking faces are supported in the direction of movement so as to give proper direction to the ball when struck with the face of the mallet.

By having all of the edges center in the same vertical plane with the handle, the maximum reinforcement is obtained at the normally weakest point of the mallet, which contains the recess to receive the handle at a point equi-distant between two striking faces.

Numerous variations may doubtless be devised by persons skilled in the art without departing from the principles of my invention. I, therefore, desire no limitations to be imposed on my invention, except such as are indicated in the appended claims.

What I claim is:

1. A mallet comprising head and handle, the head being of substantially cylindrical contour and having two striking faces, the bottom and top of said head being diamond shaped, two of the vertices of the top and bottom centering in the two striking faces, side faces of diamond shape and having two vertices of each side cen- 55

tering in said striking faces, said upper face having a recess formed therein, said handle mounted in said recess.

5 2. A mallet comprising head and handle, the head being of substantially cylindrical contour and having two striking faces, the bottom and top of said head being diamond shaped, two of the vertices of the top and bottom centering in the 10 two striking faces, the sides being concave and diamond shaped and having two vertices of each side centering in said striking faces, said upper face having a recess formed therein and said handle mounted in said recess.

15 3. A mallet comprising a head and a handle, the head being of substantially cylindrical contour and having two striking faces, the bottom and top of said head being diamond shaped, two of the vertices of the top and bottom centering in the 20 two striking faces, the sides being of diamond shape and having two vertices of each side centering in said striking faces, each striking face having the portion between said vertices removed, said upper face having a recess formed therein, said handle mounted in said recess.

25 4. A mallet comprising a head and a handle, the head being of substantially cylindrical contour and having two striking faces, the bottom and top of said head being diamond shaped, two of the vertices of the top and bottom centering 30 in the two striking faces, the sides being of diamond shape, and having two vertices of each side centering in said striking faces, said head having tapered triangular recesses formed in vertices between said striking faces, said upper face having a recess formed therein, said handle mounted 35 in said recess.

5. A mallet comprising a head and a handle, the head being of substantially cylindrical contour and having two striking faces, the bottom and top of said head being diamond shaped, two 40 and top of said head being diamond shaped, two

of the vertices of the top and bottom centering in the two striking faces, the sides being of concave diamond shape, and having two vertices of each side centering in said striking faces, said head having tapered triangular recesses formed 5 in vertices between said striking faces, said upper face having a recess formed therein, said handle mounted in said recess.

6. A mallet comprising a head and a handle, the head being of substantially cylindrical contour and having two striking faces, the bottom and top of said head being diamond shaped, two of the vertices of the top and bottom centering 10 in the two striking faces, side faces of diamond shape and having two vertices of each side centering in said striking faces, said upper face having a recess formed therein having threads, said handle mounted in said recess.

7. An article of manufacture comprising a mallet head of molded resilient material, the head being of substantially cylindrical contour and having two striking faces, the bottom and top of said head being diamond shaped, two of the vertices of the top and bottom centering in the two striking faces, side faces of diamond shape and having two 20 vertices of each side centering in said striking faces, said head having triangular sloping indents formed in the back of said striking faces and sloping toward the middle of said head, the intersection of the edges of said triangular indents 25 being in substantially the same plane.

8. A mallet comprising a head and a handle, said head having circular parallel striking faces, a pair of diametrically opposite truss members connected to said faces substantially on the plane 35 of the handle, and a second pair of diametrically opposite truss members connected to said striking faces in planes substantially perpendicular to the plane of the handle.
